UNITED STATES PATENT OFFICE.

JEAN LEON MULLER, OF SANNOIS, FRANCE, ASSIGNOR TO HIMSELF, AND JOSEPH BONNET, OF PARIS, FRANCE.

MACHINE FOR MANUFACTURING MANTLES EMPLOYED IN INCANDESCENT LIGHTING.

1,206,022.

Specification of Letters Patent.

Patented Nov. 28, 1916.

Application filed January 16, 1915. Serial No. 2,619.

To all whom it may concern:

Be it known that I, JEAN LEON MULLER, a citizen of the Republic of France, and resident of Sannois, Seine-et-Oise, France, 5 have invented a new and useful Machine for Manufacturing Mantles Employed in Incandescent Lighting, which machine is fully set forth in the following specification.

In the machine for firing, incinerating and calcining mantles intended for incandescent gas lighting, shown and described in United States Patent, No. 973,161, granted 10 jointly to Joseph Bonnet and Jean Leon Muller, motion of the parts is effected by means of chains placed on the right and the 15 left of the machine. These chains move under the thrust of a special device, on pulleys secured to the two ends of the machine, and they are at times rendered idle by automatic stopping devices, during which 20 inoperative or idle periods the various gas pipes act to fire, incinerate and calcine the mantles. While in action, the chains operate mantle supporting rods and mantle guiding rods, the ends of these rods working in 25 upper guides during their movement toward the front of the machine, and in lower guides during their movement toward the rear of the machine when the supporting rods are each provided with a series of mantles. The 30 displacement of the rods, from the upper guides to the lower guides and from the lower guides to the upper guides according to whether this operation takes place at the 35 front, in the center or at the rear of the machine, is obtained by means of elevators located on the right and left hand sides of the machine. These elevators are actuated by members called "cam rods" which 40 are susceptible of longitudinal movement in both directions. On the cam rod located on the right, for instance, and at the level of the right hand front elevator, there is fixed a chain adapted to be wound on a drum 45 mounted on the same axis as another drum having a greater diameter on which a chain is wound, the other end of which is secured to the rod of the elevator. It is evident that in each of its displacements, either forward 50 or rearward, the cam rod will cause by actuating the drums through the medium of the chains, either the lowering or raising of the elevator rod. Since the latter carries a device intended to grip and maintain the 55 end of a mantle supporting and guiding

rod, it is therefore possible to displace the said mantle supporting and guiding rods from one set of guides to another. In the form of apparatus in which the different elevators are driven by chains, it has been observed that owing to wear, expansion and other causes, the ends of the carrying and guiding rods did not reach a position facing the guides in a perfect manner after a certain time of operation of the machine. 60

The object of the present invention is to obviate the drawbacks which have been indicated above. This object is accomplished by an improved device or mechanism in which the elevator driving chains are replaced by rigid members designed to bring the ends of the mantle carrying rods and mantle guiding rods exactly into the position that these rods should occupy in the upper or lower guides. 65

The invention comprises, moreover, certain members actuated by the cam rod, and designed to place and maintain the mantle supporting and guiding rods, above each of the gas pipes of the triple gas piping for 70 incinerating purposes. 75

Finally, it comprises means for stopping the cam rod so as to avoid backward movement thereof during any of the operations of the machine, either by the action of a 85 spring or from any other cause.

The accompanying drawings show, by way of example, these various devices.

Figures 1, 2 and 3 are front elevations of the raising or lowering devices for the 90 front, center and rear elevators of the machine. Figs. 4, 5 and 6 are front and side elevations of these elevators. Fig. 7 is an elevation of the mechanism for supporting the rods above the triple incinerating piping, 95 while Fig. 8 is a plan thereof. Fig. 9 is an elevation of the stop for the cam rod, while Fig. 10 is a plan thereof.

The mechanisms illustrated in Figs. 1, 2 and 3 are duplicated and located on both the right and left hand sides of the machine, so as to produce by the displacement of the ends of the cam rods 1, an exactly similar movement. The description of the mechanisms at one side of the machine will, in consequence, answer for both sides. Each of these cam rods 1 is supported at its ends by the brackets 2 (Fig. 1) and 2' (Fig. 3). Each of these brackets is provided with spaced, upper and lower rollers 3 between 100 105 110

which the cam rod moves. The lower rollers are adjustable and steel blades or sheets 4 and 4' are fixed on the upper and lower faces of the rod ends in order to protect the 5 same against wear.

On each cam rod 1, there are fixed the 10 collars 5, 5' and 5'', each of which carries at its lower end a pivot pin or the like upon which is mounted one end of a rod 6 whose other end is pivotally connected at 7 with an 15 arm 8 mounted on the adjacent end of a horizontal rock shaft. In the case of the front device, this shaft is indicated by the numeral 9, and is journaled in brackets 10, 15 one of which is shown. The rock shaft of the central device is represented at 9', and both this shaft and the shaft of the rear device are mounted and connected up in the same general manner as the front shaft 9. 20 On the said front shaft 9 there is also keyed a lever 11 pivotally connected at 12 with the lever 13 secured at its other end, to the frame or head 14 adapted to slide on the rod 15 of the elevator. In the case where 25 owing to wear, displacement of members, etc., the ends of the mantle supporting and guiding rods should not reach a place exactly opposite that of the guides, the frame 14 may be lowered by compressing to a 30 slight extent the springs 16 and 16' without causing the displacement of the elevator. A stop 17 limits the length of the stroke of the frame 14.

The device indicated above for obtaining 35 the lowering or raising of the mantle supporting and guiding rods, is particularly applicable to the front elevators of the machine. In the other elevators, the modification to be made consists solely in the mounting 40 of the rods and levers 6 and 8, 11 and 13. In the center elevator, however, in order to maintain a constant connection between each of the members and to facilitate the operation, it is advisable to dispose on 45 the shaft 9', a drum 18 on which a chain terminated by a counterweight 19, is wound. From the above it will be quite easy to understand the operation of each of these elevators. When under the thrust of the stopping device, the cam rod 1 advances in the 50 direction indicated by the arrow α , the collar 5 moves forward with said cam rod and thereby causes the rod 6 to assume the dotted-line position 6' and the lever 8 to 55 assume the dotted-line position 8'. During this movement of the cam rod, the shaft 9 is rocked, thus swinging the lever 11 into the dotted-line position 11', said lever, in turn, forcing the rod 13 to descend and assume the dotted-line position 13'. In this 60 downward displacement, the elevator which maintained the ends of the rods in the upper guide, now causes the same to face the lower guide without allowing any deviation whatever to take place.

In Figs. 7 and 8, a safety device is illustrated, intended to obviate the inconveniences due to the continuous displacement of the rods. In fact, it has been observed that the mantle supporting and guiding rods 70 were not always perfectly connected with each other when they appeared above each of the gas pipes or the triple incinerating gas piping, and that owing to this circumstance, accidents took place in the manufacture of mantles. To this end there are disposed at the level of each of the lower guides, above the triple incinerating gas piping, two bars 20 and 20' adapted to slide along each other with a slight amount of 80 friction. These bars are supported at each of their ends by the levers 21, 21' and 22, 22' secured to the shafts 23, 24 and 25 mounted in the bearings 26 and 27. The shafts 23 and 24 are provided at their ends 85 with toothed sectors 28, 28' adapted to be rotated under the action of the arm or lever 29 fixed to the opposite end of the shaft 23, from that on which the sector 28 is mounted. A vertical rod 30 is pivoted at its upper end 31 to the arm 29, and at its lower end 33 to the arm or lever 32. This arm 32 is pivoted at 34 on the bracket 35 secured to the support 36 of the triple piping. Another arm or lever 37 integral with the 95 arm 32, carries a finger 38 which projects into a slot 39 formed in a plate or member 40 secured on the cam rod 1. The tappets 41 are fixed on the bars 20 and 20' by means of screws. These tappets are intended to 100 grip and maintain by approaching each other a supporting rod and a guiding rod for the mantles during the time necessary for the incineration of the same. This operation is effected in the following manner:—The rods 5' are operated in the lower guide c and automatically place themselves above the triple incineration gas piping. At this moment, an idle period begins, initiated by the stop device, which leaves one 110 mantle carrying rod and a guiding rod above one of the gas pipes. These rods being disposed in pairs they more or less contact with each other. It is therefore important to locate them parallelly. This result 115 is obtained by the movement of the cam rod which carries the plate 40 along with it, thus shifting the finger 38 on arm 37 owing to the special disposition of the grooves or slot 39 and causing the said lever 37 to rock 120 about its pivot 34, thereby lowering the arm 32 and the rod 30 connected thereto. The lowering of this rod causes the displacement of the toothed sectors 28 and 28' and therefore the mutual approach of the tappets 41 fixed to the parallel bars 20 and 20' which are operated by the levers 21 and 22 mounted on the same shaft as the toothed sectors. During the mutual approach of the tappets 41, the rods 5' are supported and 125 130

caused to assume the positions which they ought to occupy above each of the gas pipes and the incineration of the mantles is obtained in a perfect manner.

- 5 The device for the automatic stoppage of the cam rod so as to avoid any backward movement thereof, is shown in Figs. 9 and 10, and is constituted by a lever 42 pivoted at 43 on the same shaft as the lever 44 which 10 carries at its end the finger 45. The latter bears on a lever 46 keyed upon the same shaft as the lever 47 which forms part of the stoppage device for producing the idle period. This stoppage device corresponds, 15 in the main, to that disclosed in the said Bonnet and Muller patent, above identified, the lever 47 of the present device answering to the lever 16 of the patented construction, as shown in Figs. 4, 4^d and 4^e, and described 20 in lines 23 to 82, page 3, of the patent. Reference may be had to said patent for a complete understanding of the device in question. Upon the bracket 48 which carries the shaft 43, a rod 49 is disposed, pushed by 25 a spring 50 against the tappet 51 forming part of the lever 42. An arm 52 also carried by the lever 42 serves to control the height or extent of the stroke of the lever 42 by co-acting with a screw 53 adjustably mounted 30 on a boss carried by the bracket 48. Furthermore, upon the cam rod 1, a member 54 is fixed, designed to serve as a stop for the end 55 of the lever 42.

The device operates in the following manner:—At the moment where the idle period device abandons the cam rod 1 and pushes the same in the direction indicated by the arrow *d*, the lever 47 is lifted in the manner described in said patent, and operates in its 40 movement the lever 46 which is now lowered. The finger 45 not being any longer supported, both levers 44 and 42 are displaced under the action of the tappet 51, and the part 55 now assumes a position behind the member 54 thus rendering any backward movement of the cam rod 1, impossible.

I claim as my invention:—

1. In a machine for manufacturing incandescent mantles, the combination, with mantle supporting and guiding rods; of a cam rod; an elevator for said mantle supporting and guiding rods located at one end of said cam rod; a rigid transmission system between said cam rod and the elevator, a pair 55 of movable bars arranged to slide along each other and having instantaneous gripping means for said mantle supporting and guiding rods; mechanical connection between the said bars and said cam rod; a stopping system for the latter having instantaneously stopping means on the said cam rods; mechanism for determining the number of stoppages or idle periods of the machine; and connecting members between said stopping system and the determining mechanism.

2. In a machine for manufacturing incandescent mantles, the combination, with mantle supporting and guiding rods; of a cam rod; an elevator for said mantle supporting and guiding rods located at one end of the cam rod; a collar fixed on the cam rod; a system of pivoted levers or rods between said collar and the elevator; resilient connecting means between the last lever of said system of pivoted levers and said elevator; a pair of movable bars arranged to slide along each other and having instantaneous gripping means for said mantle supporting and guiding rods; a mechanical connection between the said bars and said cam rod; a stopping system for the latter having instantaneously stopping means on the said cam rod; mechanism for determining the number of stoppages or idle periods of the machine; and connecting members between said stopping system and said determining mechanism.

3. In a machine for manufacturing incandescent mantles, the combination, with mantle supporting and guiding rods; of a cam rod; an elevator for said mantle supporting and guiding rods located at one end of the cam rod; a rigid transmission system between said cam rod and said elevator; a pair of movable bars arranged to slide along each other; gripping tappets fixed on each of the said bars; coöperating pivoted levers and toothed sectors for effecting the simultaneous sliding movement of the said bars; an operating lever or rod for the toothed sectors; 100 a lever pivoted to the first-named lever and having a finger or toe; a member integral with the cam rod arranged to operate said finger or toe; a stopping system for the cam rod having an instantaneous stop on the said cam rod; mechanism for determining the number of stoppages or idle periods of the machine; and connecting means between said stopping system and the determining mechanism.

4. In a machine for manufacturing incandescent mantles, the combination, with mantle supporting and guiding rods; of a cam rod; an elevator for said mantle supporting and guiding rods located at one end of said cam rod; a rigid transmission system between said cam rod and said elevator; a pair of bars arranged to slide along each other and having instantaneous gripping means for said mantle supporting and guiding rods; a mechanical connection between said bars and the cam rod; a stopping system for the cam rod having a finger or toe; a spring arranged to draw said finger or toe toward the cam rod; a shoulder or stop on the cam rod for stopping the said finger or toe; a retaining system for said finger or toe; mechanism for releasing the same; mechanism for determining the number of stoppages or idle periods of the machine; 130

and a connecting lever between said releasing mechanism and the determining mechanism.

5. In a machine for manufacturing incandescent mantles, the combination, with mantle supporting and guiding rods; of a cam rod; an elevator for said mantle supporting and guiding rods located at one end of the cam rod; a collar fixed on the cam rod; a system of pivoted levers or rods between the said collar and the elevator; a resilient connecting means between the last lever of said system of pivoted levers and said elevator; a pair of bars arranged to slide along each other; gripping tappets fixed on each of said bars; coöperating pivoted levers and toothed sectors for effecting the simultaneous sliding movement of said bars; an operating lever or rod for the toothed sectors; a lever pivoted to the first-named lever and having a finger or toe; a member integral with the cam rod arranged to operate said finger or toe; a stopping system for the cam rod having an instantaneous stop on the said cam rod; mechanism for determining the number of stoppages or idle periods of the machine; and connecting means between said stopping system and said determining mechanism.

30. 6. In a machine for manufacturing incandescent mantles, the combination, with mantle supporting and guiding rods; of a cam rod; an elevator for the mantle supporting and guiding rods located at one end of the cam rod; a collar fixed on the cam rod; a system of pivoted levers or rods between said collar and the elevator; a resilient connecting means between the last lever of the system of pivoted levers and the elevator; a pair of bars arranged to slide along each other and having instantaneous gripping means for the mantle supporting and guiding rods; a connection between said bars and the cam rod; a stopping system for said cam rod having a finger or toe; a spring arranged to draw said finger or toe toward the cam rod; a shoulder or stop on the cam rod for stopping said finger or toe; a retaining system for said finger or toe; mechanism for releasing the same; mechanism for determining the number of stoppages or idle periods of the machine; and a connecting lever between said releasing mechanism and the determining mechanism.

55 7. In a machine for manufacturing incandescent mantles, the combination, with
mantle supporting and guiding rods; of a
cam rod; an elevator for the mantle sup-
porting and guiding rods located at one
60 end of the cam rod; a rigid transmis-

sion system between said cam rod and said elevator; a pair of bars arranged to slide along each other; gripping tap-pets fixed on each of the said bars; co-operating pivoted levers and toothed sectors 65 for effecting the simultaneous sliding move-
ment of said bars; an operating lever or rod for the toothed sectors; a lever pivoted to the first-named lever and having a finger or toe; a member integral with the cam rod ar- 70 ranged to operate said finger or toe; a stop-
ping system for the cam rod having a finger or toe; a spring arranged to draw the last-named finger or toe toward the cam rod; a shoulder or stop on the cam rod; a retain- 75 ing system for the said last-named finger or toe; mechanism for releasing the same; mechanism for determining the number of stoppages or idle periods of the machine; and a connecting lever between said releas- 80 ing mechanism and the determining mecha-nism.

8. In a machine for manufacturing incandescent mantles, the combination, with
mantle supporting and guiding rods; of a cam rod; an elevator for the mantle supporting
and guiding rods located at one end of the cam rod; a collar fixed on said cam rod;
a system of pivoted levers or rods between said collar and the elevator; a resilient connecting
means between the last lever of the system of pivoted levers and said elevator; 90
a pair of bars arranged to slide along each other; gripping tappets fixed on each of the
said bars; coöperating pivoted levers and toothed sectors for effecting the simultaneous
sliding movement of said bars; an operating lever or rod for the toothed sectors; a
lever pivoted to the first-named lever and having a finger or toe; a member integral 100
with the cam rod arranged to operate said finger or toe; a stopping system for said
cam rod having a finger or toe; a spring arranged to draw the last-named finger or toe
toward the cam rod; a shoulder or stop on said cam rod for stopping said last-named
finger or toe; a retaining system for the said last-named finger or toe; mechanism for re-
leasing the same; mechanism for determining the number of stoppages or idle periods 105
of the machine; and a connecting lever between said releasing mechanism and the determining
mechanism. 110
